UNITED STATES PATENT OFFICE.

WILLIAM H. WYTHE, OF GLENRIDGE, NEW JERSEY, ASSIGNOR TO THE REPEATING TORPEDO & NOVELTY CO., OF EAST ORANGE, NEW JERSEY.

TOY PISTOL.

SPECIFICATION forming part of Letters Patent No. 680,126, dated August 6, 1901.

Application filed February 15, 1900. Serial No. 5,261. (No model.)

To all whom it may concern:

Be it known that I, WILLIAM H. WYTHE, a citizen of the United States of America, residing at Glenridge, Essex county, State of New Jersey, have invented a new and useful Improvement in Toy Pistols, of which the following is a full, clear, and exact description, reference being had to the accompanying drawings, forming a part of this specification.

10 My invention relates to that class of toy pistols known as "repeating" pistols, and contemplates a toy which shall be simple and inexpensive in its construction and safe, simple, and durable in its operation and which 15 shall produce a series of detonations from a single loading.

Figure 1 is a view showing my pistol partially in vertical section and part in side elevation. Fig. 2 is a side elevation. Fig. 3 is 20 a plan view.

Referring to the drawings, A is a marble or other hard sphere provided with a surface composition, as described and claimed in my application, Serial No. 702,181, filed January 25 14, 1899, the same being coated with a detonating compound so composed that it will only explode at a point of impingement.

B C indicate the framework of the pistol, composed of two castings of iron or other suitable material fastened together by rivets or screws a b, said castings being formed with a cup or depression in which the ball A is loosely supported.

The hammer E, which is pivoted to the 35 framework of the pistol by a rivet or pin c, preferably cast as a part of one of the sides thereof, is normally held, as shown in Fig. 1, with its upper end bearing against the ball A under the action of spring G. As shown,

40 one end of spring G is given a fixed connection or support within the pistol-frame by lugs or projections f f, which preferably are also cast as a part of the framework. i is a piece of rubber or other suitable material in-

45 inserted between the spring F and the trigger, which serves to impart rotation to the ball, although it may be omitted, as the upper portion h of the trigger D contributes to and may serve this purpose.

50 A trigger D is loosely pivoted within the

frame by a rivet or pin d, the journal-opening e being elliptical in form. The trigger is normally held in contact with the hammer by a spiral spring F, one end of which is inserted in an opening k in the frame, or it may be otherwise suitably secured against the said frame, while the other end of said spring passes through a hole in the upper portion h of the trigger. A shoulder or projection g engages a corresponding notch l on the hammer E.

The operation of the device is as follows: As the trigger is pulled the spiral spring F is compressed, the projection g engages with the notch l, raising hammer E until said projection slips past said notch, when the hammer is released and by the action of the flat spring G strikes against the ball A, causing a detonation at its point of contact. The pulling of the trigger also engages the upper portion of the arm h of the trigger with the ball A, causing it to revolve and present a fresh or unexploded portion of its coating to the hammer. When the trigger is released, the elliptical journal e permits the projection g to pass over the notch l, and the expansion of the spiral spring F throws the said trigger back to its initial position. This arrangement enables the operator to explode the detonating material on the ball as rapidly as desired and as long as any of the coating thereof remains.

The cup-shaped receptacle for the ball is cast with a raised portion H, which acts as a shield to prevent sparks from flying in the face of or against the hand of the operator when the detonation or explosion takes place.

What I claim, and desire to secure by Letters Patent, is—

1. In a detonating toy, the combination of 90 a frame, a cavity therein, a ball coated with detonating material loosely contained in said cavity, a hammer pivoted on said frame and adapted to strike said ball and means for propelling said hammer against said ball, substantially as described.

2. In a detonating-pistol, the combination of a stock, barrel and trigger, a cavity in the frame of said pistol, a ball provided with detonating composition loosely contained within 95 100

said cavity, a hammer actuated by said trigger, and means whereby said ball is revolved in every direction to present a different part of the surface of said ball to said hammer at 5 each successive operation of the pistol.

3. In a detonating-pistol, the combination of the frame thereof, a ball provided with detonating composition, a receptacle in which said ball is loosely contained, and frictional 10 engaging means to revolve said ball, as and for the purpose set forth.

4. In a detonating-pistol, the combination of the frame thereof, a trigger and hammer, springs for said trigger and hammer, a ball 15 provided with detonating composition, a receptacle in which said ball is loosely contained, frictional engaging means for revolving said ball, and a shield or guard, as and for the purpose set forth.

20 5. In combination with a ball provided with a coating of detonating material, a receptacle in which said ball is adapted to be loosely

contained, a hammer mechanism for striking said ball consisting of a hammer, a trigger, pivots and springs for said hammer and trigger and frictional means for rotating said ball actuated by said trigger, substantially as set forth.

25 6. In a detonating toy, the combination with a frame, a cavity therein, a ball coated with detonating material loosely contained in said cavity, a hammer pivoted on said frame and adapted to strike said ball, a trigger for actuating said hammer, and frictional material carried by said trigger for rotating said ball 30 upon the movement of said trigger, substantially as described.

In testimony whereof I have signed my name to this specification in the presence of two subscribing witnesses.

35 WILLIAM H. WYTHE.
